UNITED STATES PATENT OFFICE.

EDWARD A. TUCKER, OF WINCHESTER, MASSACHUSETTS.

CONCRETE BUILDING CONSTRUCTION.

1,244,663.

Specification of Letters Patent.

Patented Oct. 30, 1917.

Application filed December 7, 1911. Serial No. 664,341.

To all whom it may concern:

Be it known that I, EDWARD A. TUCKER, a citizen of the United States, and a resident of Winchester, county of Middlesex, 5 Commonwealth of Massachusetts, (whose post-office address is 683 Atlantic avenue, Boston, Massachusetts,) have invented an Improvement in Concrete Building Constructions, of which the following description, 10 in connection with the accompanying drawings, is a specification, like characters on the drawings representing like parts.

This invention relates to concrete building construction and consists more particularly in the provision of improved methods and means for molding portions of a concrete structure such, for example, as the floor panels, beams, walls, columns and the like.

20 In the molding of concrete floors it has been usual to provide wooden or, in some cases, metallic forms. These are expensive to erect and costly in themselves, and, when the structure is complete, must be removed; 25 or, if left in place, they constitute dead weight without adding to the strength of the structure. One object of the present invention is the provision of a previously molded form, preferably of concrete, which can be used in place of the wooden or metal form, thereby saving a large part of the present cost of erecting complete wooden forms. Such molded form, moreover, can not only 30 be left in position after the structure is complete, but can be so bonded to the therein molded part of the structure as to form a component and integral part of the monolith, contributing to the strength and load-sustaining capacity thereof. Such molded 35 forms are preferably reinforced and can be manufactured in portable form, suitable to withstand shipment to distant points from the place of production, and may be made in units of such size as to be adapted for a 40 large variety of commercial purposes.

In the common construction of a monolithic floor panel where it is required to core out portions of the material below the neutral axis of the floor slab and between the 45 reinforced ribs on the under side of the floor, for the purpose of removing dead weight from the slab, such molded forms may be constructed to constitute at the same time forms and cores for the floor slab, and thereby avoid the use of cores of tile or other ma-

terial, which remain in the completed floor as so much dead weight.

The invention will be best understood by reference to the following description, when taken in connection with the accompanying 60 illustration of one specific embodiment thereof, while its scope will be more particularly pointed out in the appended claims.

In the drawings:

Figure 1 is a perspective view, partly in 65 section, showing the application of one form of the invention to a cored out floor panel, where the ribs run in two directions at right angles to each other;

Fig. 2 is a section in elevation, taken 70 lengthwise through one of the upper core-form members;

Fig. 3 is a similar section, taken in a plane at right angles to the section of Fig. 2; and

Fig. 4 is a detail view showing one of the 75 filler blocks.

Referring to the embodiment of the invention selected for illustration, and first more particularly to Figs. 1 to 4 inclusive, I have there shown its application to the 80 formation of a floor panel comprising the slab 1, having the reinforced ribs 2 on its under side and the reinforced cross ribs 3 extending at right angles thereto, intermediate portions of the under side of the slab 85 being cored out to remove the dead weight of concrete therefrom.

A floor panel of this type is ordinarily molded by means of a wooden form, which is carefully built up to form the under side of 90 the slab and also to provide the box-like core portions; or the cores may be provided by means of cast or molded blocks or tile or metal blocks, which rest directly upon a wooden form.

Herein I have provided a series of core-forms, which, having been previously molded out of concrete and allowed to harden, are placed in position and caused to rest upon any suitable skeleton support such as the 100 wooden ledger boards.

The concrete core-forms may be manufactured in units of any suitable size according to the dimensions of the panel, and may be assembled from any desired number of 105 parts or from parts having various shapes. Herein, by way of illustration, I have shown core-forms the walls of each of which are formed by the assemblage of a lower core form-member, having the bottom 5 and up- 110

right sides 6, and an upper core-form member having a succession of flat faces 7, separated by U-shaped depressions. These core-form members may be made in any required length to suit different conditions, but in the illustrative form each upper core-form member has four faces 7 (Fig. 2), which coöperate respectively with four separate lower core-form members to form four box-like core units, longitudinally separated by the U-shaped depressions, the side walls 8 and bottom wall 9 of which constitute rib-forming walls for the transverse ribs 3.

The bottoms 5 of the lower core-form members are extended at each side to form flanges 10, and these are of such a width that when the adjacent units are assembled with the edges of the flanges in abutment, as shown, the sides 6 of adjacent units with the flanges 10 constitute rib-forming walls for the longitudinal ribs 2.

Any suitable support or arrangement of supports may be utilized for the described core forms, dependent upon the dimensions and shape of the latter, but herein pairs of adjacent ledger boards 4 are provided, running in the direction of the flanges 10, and so located that each flange rests upon the upper edge of an underlying supporting board 4.

To fill in the space between the flanges 10 and the bottom walls of the upper form member the flanges 10 may be prolonged beyond the sides 6 or the walls 9 may be provided with lateral extensions or feet to fill such spaces. Herein, however, separate form filling blocks 9^x are employed (see Fig. 4) of a size suitable to fill the intervening space. To support the weight of the concrete when applied to the form such blocks may be sustained in any desired way, but herein they are shown as provided on each edge with an angle piece 10^x embedded in the block and having a projecting part adapted to rest on the top of adjacent faces 9 or 10 and be sustained thereby.

The core-forms are preferably reinforced so as to be capable of transportation and shipment, as well as to be self-supporting when assembled and to support their own weight and the weight of the concrete when poured thereon while at the same time spanning an appreciable or substantial space between the supports on which they rest. In the illustrated embodiment of the invention transverse reinforcement 11 is provided for the bottom 5 and the flanges 10 of the lower core form, longitudinal reinforcement 12 for the faces 7 of the upper core form, and both longitudinal and upright reinforcement 13 for the sides 8 of the U-shaped depressions and the sides 6 of the lower member.

These core-forms may be made at a distance and shipped to the point of use. They may be formed of cement, with or without

crushed stone or aggregates, the term "concrete" as used herein including not only mixtures of cement with a large proportion of aggregates, but also cement alone with little or no aggregates.

70

By taking simple and well-known precautions such, for example, as wetting the walls of the core-forms just prior to molding the floor slab, and preliminarily applying thereto a thin grout before introducing the major part of the concrete material, or utilizing any other well-known means for accomplishing the same end, the previously molded core forms may be so bonded to the freshly molded part of the slab as to constitute an integral part thereof, and supply a portion of the load-sustaining material of the slab. Where desired, the core forms may be constructed omitting the bottom pieces 5 so that the under side of the ceiling has a paneled effect, but in the form shown the completed floor slab presents a smooth under side, with air spaces between the ribs where the cores have been used. This forms a floor slab of given strength with the minimum amount of concrete material and at the lowest possible expense.

75

80

85

90

95

The same principle of utilizing concrete forms may be employed in molding a floor beam, or any other structural element. In Fig. 1, I have shown a floor beam 14, which borders the floor slab 1, such floor beam having a form consisting of the previously molded concrete sides 15 and the bottom member 16, which latter may be of wood, metal or concrete. The sides are provided with upper flanges 15^x with which the edges of the flanges 10 of adjacent core forms are brought into abutment.

100

In the instance submitted for illustration the floor panel is bordered on each of its four sides by a beam like the beam 14, there being contained between these beams a suitable number (such, for example, as eight) rows of core units, each row comprising eight core units assembled from two upper core members 7 with the corresponding eight lower core members. My invention, however, is independent of the particular number or assemblage of the core-units, these factors varying in practice with the dimensions of the panel and other conditions.

105

110

115

To assist in assembling the core-form members suitable fastenings may be employed if desired, and in Fig. 1, I have shown metal strips or wires 17 embedded in the upper edges of the sides 6 of the lower form member, such strips having free projecting ends which may be wrapped about or fastened to pins 17^x or other suitable members embedded in the overlying faces 7 of the upper core form member.

120

125

With the construction shown in Fig. 1 the ceiling may be left unplastered if de-

130

sired, the resulting surface being substantially smooth and unbroken.

By arranging the reinforcement for the core form with reference to strengthening the floor slab as well as sustaining the form itself while being shipped, set up, and used, the floor slab may be greatly strengthened and the distance between adjacent floor ribs considerably increased without the necessity 10 of additional reinforcement for the slab.

While I have described my invention as applied to a floor construction employing the additionally molded slab portion 1 which, in conjunction with the top faces of 15 the core-forms, constitutes the floor slab, in certain cases the additionally molded slab portion might be omitted entirely, as, for example, in house construction where suitable reinforced top faces of the core-forms 20 with the subsequently molded material which bridges these faces might be relied upon to constitute the floor slab.

It is obvious that previously molded hardened forms similar to those employed 25 for molding the sides of the beams 14 might be employed for molding upright columns as well as other structural elements.

The illustrative embodiments of the invention are merely examples of the many 30 different ways in which the same principle can be applied. In both cases, however, it will be seen that the previously molded units constitute forms for molding the floors, beams or other structural elements. 35 Where used for molding the floor slab as described, such units also constitute cores for coring out the dead weight of the floor slab below the neutral axis and between the intervening reinforced ribs. More wood or 40 other material may be required in some instances than in the cases illustrated to support the molded core forms where different dimensions or different types of forms are employed, but the amount of wood and expense of preparing the forms in any event 45 may be made less than with the previously employed wooden or metallic forms.

While I have herein shown and described 50 for purposes of illustration one specific form of the invention, it is to be understood that the same is submitted for illustrative purposes only and that extensive deviations may be made therefrom without departing from the spirit of the invention.

Claims:

55

1. A concrete floor construction for a floor slab including a plurality of integral, reinforced concrete members having each a plurality of substantially flat slab-forming faces with intervening rib-forming depressions adapted to form ribs in one direction, said members being separated to form ribs in the opposite direction, and other concrete form members presenting a depressed, U-shaped formation between said 60 slab forming faces to coöperate with the first mentioned members to provide forms for the said oppositely directed ribs, and a subsequently molded slab constituting a monolith with said core-form members, said 65 first-named concrete members constituting both forms to be supported at their ends to span a substantial space and sustain the weight of the intervening concrete when poured and a core to core out the dead 70 weight from the flat slab.

2. A concrete floor construction for a floor slab including a plurality of integral, reinforced concrete members having each a plurality of substantially flat slab-forming 80 faces with intervening rib-forming depressions adapted to form ribs in one direction, said members being separated to form ribs in the opposite direction, and other concrete form members to coöperate with the first- 85 mentioned members and comprising each upright sides and projecting flanges, the flanges of adjacent members approaching each other to provide with said sides the forms for said oppositely directed ribs and 90 comprising also bottom walls separated from said slab members by said upright sides and adapted to form a flat ceiling, and a subsequently molded slab constituting a monolith with said core-form members, said 95 first-named concrete members constituting both forms to be supported at their ends to span a substantial space and sustain the weight of the intervening concrete when poured and a core to core out the dead 100 weight from the flat slab.

In testimony whereof, I have signed my name to this specification, in the presence of two subscribing witnesses.

EDWARD A. TUCKER.
